UNITED STATES PATENT OFFICE.

JOSEPH C. BARRETT, OF BROOKLYN, NEW YORK, ASSIGNOR TO BULKRUG MACHINE CORPORATION, OF NEW YORK, N. Y., A CORPORATION OF NEW YORK.

POWER-TRANSMITTING MECHANISM.

Application filed April 10, 1922. Serial No. 551,420.

My invention relates to improvements in the class of power transmitting means set forth in U. S. Letters Patent to William Buhl, No. 1,347,076, granted July 20, 1920, and No. 1,349,661, granted Aug. 17, 1920, wherein a rotative pin cooperates with a cam groove to reciprocate a block to operate a hammer.

One object of my invention is to render the operation of the reciprocative block by the pin more free and with reduced friction, and other objects are to provide improved driving means for such pin and generally to improve the class of mechanism referred to.

My invention comprises novel details of improvement that will be more fully hereinafter set forth, and then pointed out in the claims.

Reference is to be had to the accompanying drawing, forming part hereof, wherein—

Figure 1 is a partly sectional side view of a power transmitting mechanism embodying my invention;

Fig. 2 is a section substantially on line 2, 2, in Fig. 1;

Fig. 3 is a transverse section taken approximately on the irregular line 3, 3, in Fig. 1;

Fig. 4 is a side elevation looking from the left in Fig. 1;

Fig. 5 is a detail perspective view of the cam member looking from the right hand side in Fig. 1;

Fig. 6 is a view similar to Fig. 5 part being omitted;

Fig. 7 is a detail section of the crank pin member;

Fig. 8 is a section illustrating means for operating a drill as well as a hammer, and Fig. 9 is a section on line 9, 9 in Fig. 8.

Similar numerals of reference indicate corresponding parts in the several views.

The numeral 1 indicates a suitable casing to contain the transmitting mechanism, and at 2 is a motor adapted to be securely attached to said casing, which may be an electric or fluid motor. The casing is shown

provided with a removable front plate 3 detachably retained by screws or bolts. In Fig. 8 the casing has a removable back plate 4 which may be retained by bolts. The casing is also provided with a depending tubular guide member 5, which may be de-

tachably retained by bolts at 6. Within the casing is a reciprocative cam member 7 provided with a depending hammer or plunger 8, that is guided within and by the guide 5. Hammer 8 is shown longitudinally fluted or grooved at 8^a for the passage of air. The hammer opposes the end of a tool A within guide 5, such as a drill or riveter, the tool having a groove a receiving a spring pressed ball 10 to retain the upper end of the tool in guide 5, (Fig. 1). The member 7 has parallel sides 7^a engaging anti-friction rolls 11 journaled on screws 12 supported by the casing, being shown attached to plate 3. The hammer 8 being guided in guide 5 and the member 7 guided between rolls 11 provides effective means for reciprocation of member 7 and the hammer with relatively small friction. The member 7 is provided with a curved cam slot 7^b or groove 7^b within which operates a projection or crank pin 13 shown extending from a crank disk 14 supported in anti-friction bearings 15, 15^a, within casing 1. Crank-pin 13 is shown provided with an anti-friction sleeve or roll 13^a to operate in slot 7^b. The shape of cam-slot 7^b is somewhat of the general character of the cam slot shown in the aforesaid Letters Patent, whereby when projection 13 is rotated within said slot the cam member 7 will be reciprocated to reciprocate hammer 8. I make a portion of the wall of cam slot 7^b movable for cooperation with projection 13 to reduce friction and wear between the parts, for which purpose I provide member 7 with a roller 16 shown journaled upon a projection or stud 17 preferably formed integral with member 7. The periphery of roller 16 is on the same, or substantially the same, curve as surface 7^c of slot 7^b, both described around the axis of the roller, so that with the periphery of the roller 16 and the opposing spaced curved surface 7^c the main working surfaces of cam slot 7^b are provided for operation of projection 13. When projection or crank pin 13 is rotated with disk 14, in the direction of the arrow in Fig. 2 resistance to the rotation of said projection will be relieved by its engagement with roller 16 which will rotate as the projection or crank pin travels in engagement with the roller. During a relatively large portion, say two-thirds, of a rotation of projection or crank pin 13 in engage-

ment with the left hand side and lower portion of movable wall or roller 16 as viewed in Fig. 2 retreat of member 7 with hammer 8 from the work is effected, the crank-pin 5 then being free from surface 7^a and during the remainder, or nearly so, of said rotation of the crank pin it operates against cam surface 7^c to force the member and hammer to the work with a blow or greatly increased 10 speed, the crank-pin then being free from roller 13. Thus the crank-pin during its eccentric travel successively engages the movable wall or roller 16 and the surface 7^c. The cam slot is shown formed by means of 15 a recess 18 formed within one face of member 7, (Figs. 5 and 6), within which recess the roller 16 is journaled upon stud 17 extending from a wall of said recess. As the portion of member 7 above or beyond crank- 20 pin 13 is inoperative with said pin the cam-slot is shown widened, so that the walls of the cam-slot are free from the crank-pin at the moment of impact of the hammer, and metal above may be dispensed with, (Fig. 25 2), since the cam slot 7^b may open through the upper or outer edge of member 7. In other words, since at about the moment of impact of the hammer the crank-pin is released from cam member 7 in the upper part 30 of the cam-slot the metal beyond the crank-pin 13 may be omitted, as distinguished from the construction shown in the aforesaid patents to Buhl.

Means are provided to rotate crank-disk 35 14 at a speed reduced from the speed of the motor shaft 2^a, as follows:—Disk 14 has a worm gear or wheel 22 in mesh with a worm 23 whose shaft 23^a is journaled in bearings in casing 1. The bearing 23^b is detachable 40 to admit worm 23 to step its shaft below, (Fig. 1), at bearing 23^d. The worm 23 extends at an angle to the axis of member 7 and worm gear 22. Shaft 23^a is shown provided with a squared projection 23^c, (Fig. 45 1), to receive the corresponding recessed end of shaft 2^a of motor 2 when the motor casing is applied to casing 1. The motor casing 2^c is shown secured to casing 1 at the end opposite guide 5, and a handle B is 50 shown attached to the motor casing so that the operator may press the tool to the work bodily. Handle B is shown provided with terminals or binding posts b for the line conductors and the leads for the motor.

55 In the construction described the worm gearing described is permanently operative between the motor and crank disk 14, so that when the motor circuit switch (not shown but preferably carried on handle B 60 in an ordinary way) is closed the member 7 will be reciprocated by the rotation of projection 13 within its cam slot or recess.

65 In the form shown in Figs. 8 and 9 means are provided to operatively connect disk 14 with the motor shaft and to disconnect them.

As shown in Figs. 8 and 9 the disk 14 has a hub 14^a journaled within a sleeve 20, the outer end of which is journaled in a bearing 21 in casing 1. Sleeve 20 carries worm gear 22. The free end of hub 14^a is provided with clutch member 14^b, (Fig. 8) to be engaged by clutch members 24^a on slidable members 24 within sleeve 20. The clutch member 24 is rotative by sleeve 20 by means of one or more studs or screws 25 70 extending from member 24 and operative in corresponding slots 20^a in sleeve 20, (Fig. 8). The inner ends of said studs or screws project within a bore in member 24 to engage a groove 50^a in a head 50 slidable in 75 said bore. The stem 26 of head 50 projects through a bearing 27 in casing 1 in position to enable its outer end to be grasped. The stem 26 is provided with annular grooves 80 26^a to receive a stop 29, shown in the form of a ball, pressed by spring 30 against stem 26. When the parts are in the position shown in Fig. 8 the tool will be idle. When clutch members 14^b, 24^a are in engagement 85 the sleeve 20, through studs 25 and said clutch members, will rotate disk 14 and crank pin 13 to actuate cam member 7. When stem 26 is pulled outwardly said clutch members will be disengaged to permit motor 2 to continue to rotate without 90 operating cam member 7.

A further feature of my invention is that the machine may be provided with means for rotating a drill separately from the operation of the hammer, as desired. In Figs. 8 100 and 9 a driving clutch member or sleeve 37 is shown journaled in bore 20^b of sleeve 20 and provided at its inner end with clutch teeth 37^a to engage clutch teeth 24^c on member 24. The clutch teeth 14^b and 37^a are so spaced that member 24 may be in a neutral position therebetween or may be shifted to teeth 14^b or to teeth 37^a to cause rotation of hub 14^a or sleeve 37. The member or sleeve 37 is provided with gear teeth 38 in mesh 105 with gear 39 carried by shaft 40 journaled in suitable bearings 41 in casing 1. Shaft 40 is shown provided with means, comprising a spindle 42 and chuck 43, to receive a 110 drill or tool 44 (Fig. 8). Shaft 40 and tool 44 are shown extending in a direction different from the plane of the hammer, so that one may be used without interference by the other.

When the hammer is to be used the clutch teeth 14^b, 24^a, are engaged by pushing stem 26 inwardly for actuating cam member 7, as before described, and the drill will not operate. When the drill 44 is to be used clutch teeth 24^c and 37^a are engaged by pulling out stem 26, and the hammer will not operate. Different characters of work may be performed with a single portable instrument having a single motor without unduly increasing the dimensions or weight thereof. 120 125 130

The construction described is such that guide 5 may be removed as a unit from the hammer, the casing and front plate, and said plate may be removed for access to cam member 7 which may be removed from crank-pin 13, and said pin may be withdrawn from disk 14 through the front opening of the casing. The worm 23 may be removed through the top opening of the casing, and the clutch member 24 may be removed through the rear opening of the casing after the rear plate 4 has been removed. The disk 14 and its worm may be removed through the front casing opening. The sleeve 20 may be removed with one of the ball bearings 15 or 21 through the front or rear opening of the casing. The parts may be correspondingly assembled in the casing.

My improvements provide a compact and strong tool, not liable to get out of order, and affording improved means for actuating the hammer member 7 with minimum of friction and danger of breakage.

Changes may be made in the arrangements set forth without departing from the spirit of my invention.

Having now described my invention, what I claim is:

1. A power transmitting mechanism comprising a reciprocative member provided with a cam slot having curved spaced walls, a wall of said slot being movable, an eccentric pin operative in said slot in cooperation with said walls, said slot at the upper portion at the movable wall being of greater width than the diameter of the pin to release the latter, and means to actuate said pin, the said pin being operative against a side and lower portion of the movable wall to cause retreat of the member.

2. A power transmitting mechanism comprising a reciprocative member provided with a cam slot, a roller journaled on said member, a portion of said roller forming part of the wall of said slot, said slot having a curved surface opposing the roller, an eccentric pin operative in said slot in cooperation with said roller, and means to actuate said pin, the said pin being located to successively engage a side and lower portion of the roller and said curved surface to reciprocate the member.

3. A power transmitting mechanism comprising a reciprocative member provided with a cam slot, a roller journaled on said member, a portion of said roller forming part of the wall of said slot, the periphery of the roller and a portion of the opposing surface of the slot being on substantially similar curves described around the axis of the roller, a crank-pin in said slot cooperative successively with a side and lower portion of said roller and with said surface to reciprocate the member, and means to rotate

said pin, the upper portion of the slot releasing the pin at the moment of impact of the member.

4. A power transmitting mechanism comprising a reciprocative member provided with a cam slot, the member having a hammer, walls of the slot being in the axis of the hammer, the outer portion of said slot being open through the member, a crank-pin operative in said slot, the slot having a portion wider than the pin to release the latter during impact of the hammer, and means to rotate said crank-pin.

5. A power transmitting mechanism comprising a casing, a reciprocative member having parallel side edges and provided with a hammer, the casing having spaced rollers receiving and guiding said side edges therebetween, a guide carried by the casing receiving and guiding said hammer, and means to reciprocate said member and hammer.

6. A power transmitting mechanism comprising a casing, a reciprocative member and hammer, means to guide said member and hammer, a disk having a crank-pin and a hub, the member having a cam-slot receiving said pin, said slot having a portion to release the pin during impact of the member a sleeve cooperative with said hub, means to operatively connect the sleeve and hub, and means to rotate said sleeve.

7. A power transmitting mechanism comprising a casing, a reciprocative member and hammer, means to guide said member and hammer, a disk having a crank-pin and a hub, the member having a cam-slot receiving said pin, said slot having a portion to release the pin during impact of the member, a sleeve cooperative with said hub, means to operatively connect the sleeve and hub, said sleeve having a worm wheel, and a worm meshing with said wheel.

8. A power transmitting mechanism comprising a casing, a reciprocative member and hammer, means to guide said member and hammer, a disk having a crank-pin and a hub, the member having a cam-slot receiving said pin, said slot having a portion to release the pin during impact of the member, a sleeve cooperative with said hub, a clutch member slidable in said sleeve to cooperate with said hub, means connecting said sleeve with said clutch member to rotate the latter, and means to rotate said sleeve.

9. A power transmitting mechanism comprising a casing, a reciprocative member and hammer, means to guide said member and hammer, a disk having a crank-pin and a hub, the member having a slot receiving said pin, a sleeve cooperative with said hub, a clutch member slidable in said sleeve to cooperate with said hub, a stud projecting from said clutch member into a slot in the

sleeve, a shifting head rotatively united to said clutch member, and means to rotate said sleeve.

10. A power transmitting mechanism comprising a casing, a reciprocative member and hammer, means to guide said member and hammer, a disk having a crank-pin and a hub, the member having a slot receiving said pin, a sleeve cooperative with said hub, a clutch member slidable in said sleeve to cooperate with said hub, a stud projecting from said clutch member into a slot in the sleeve, a shifting head rotatively united to said clutch member, said head having a stem projecting through the casing, and means to retain said stem in different set positions.

11. A power transmitting mechanism comprising a casing, a reciprocative member to operate a hammer, means to reciprocate the member, a shaft separate from said means to operate a tool, gearing and a motor to actuate said means and tool, and means operative to cause said gearing to actuate said means and said tool separately.

12. A power transmitting mechanism comprising a casing, a reciprocative member to operate a hammer, a sleeve, gearing and a motor to actuate said sleeve, a second sleeve, a shaft to operate a tool, gearing between said second sleeve and shaft, and clutch means to cause the first named sleeve to actuate the hammer and the second named sleeve separately.

13. A power transmitting mechanism comprising a casing, a reciprocative member to operate a hammer, a hub, means operative between the hub and said member to actuate the latter, a second sleeve, clutch means to operate the hub and the second named sleeve separately by the first named sleeve, a shaft for a tool, and gearing between said shaft and second named sleeve.

14. A power transmitting mechanism comprising a casing, a reciprocative member to operate a hammer, a shaft to operate a tool, a hub within said sleeve provided with clutch teeth, means between said hub and member for operating the latter by the former, a clutch member operative within

said sleeve, means to rotate the clutch member by said sleeve, a second sleeve operative within the first named sleeve and having clutch teeth cooperative with said clutch member, and gearing between said shaft and said second named sleeve, said clutch member being movable with relation to said clutch teeth to cause operation of said hub and the second named sleeve separately.

15. A power transmitting mechanism comprising a casing, a member operative in the casing to actuate a hammer, a shaft for a tool journaled in the casing at an angle to said member, a motor, gearing to actuate said member and shaft, and clutch means to cause said gearing to actuate said member and said shaft separately.

16. A power transmitting mechanism comprising a casing, a reciprocative member provided with a cam slot and a hammer, the casing having guiding means for said member, a guide for the hammer extending from one side of the casing, a rotative member within the casing and provided with a crank pin operative in said cam slot, a worm gear to actuate said rotative member, a worm in mesh with said gear and extending at an angle to the axis of said rotative member, a motor and its casing attached to the first named casing on the side opposite said guide, means to rotatively connect said shaft and worm, and a handle on said motor casing.

17. A power transmitting mechanism comprising a reciprocative member provided with a recess located within one face of said member and having a projection within said recess, a roller journaled on said projection within said recess and spaced from a wall of said recess, said roller and said wall forming a cam-slot, a crank-pin operative in said slot successively against its said wall and the roller, the cam-slot being wider than the pin to release the pin for impact of the member, and means to rotate said crank-pin.

Signed at New York city, in the county of New York and State of New York, this 5th day of April, A. D. 1922.

JOSEPH C. BARRETT.
